AUTOMATIC FEEDING DEVICE FOR LIQUID
FUEL AND THE LIKEThomas F. Spackman, River Grove, Ill., assignor
to Stewart-Warner Corporation, Chicago, Ill.,
a corporation of Virginia

Application November 12, 1936, Serial No. 110,548

5 Claims. (Cl. 103—26)

This invention relates to liquid feeding means adapted for delivering fuel oil to a burner in which it is utilized. One purpose of the invention is to provide means for automatically controlling the delivery of fuel to meet the requirements of the burner. Another object is to provide means for automatically stopping the flow of fuel when the demand exceeds the maximum rate of supply, as in the event of leakage in the fuel line or imperfect control at the burner. A further object is to prevent flooding of the apparatus in the event that the float which normally controls it fails to function. The invention consists of certain features and elements of construction in combination, as herein shown and described and as indicated by the claims.

In the drawings:

Figure 1 is a side elevation of an apparatus embodying this invention and including a covered fuel bowl, or with fuel flow connections adapted to extend from a source of supply and to a burner to be served.

Figure 2 is a top plan view of the apparatus with the cover removed.

Figure 3 is a vertical section taken as indicated at the line 3—3 on Figure 1.

Figure 4 is a top plan view of the cover.

Figure 5 is an inverted or bottom plan view of the cover.

Figure 6 is a detail section of the cover taken as indicated at line 6—6 on Figure 4.

Figure 7 is a bottom view of the bowl or receptacle.

Figure 8 is a top plan view of the bowl with the mechanism removed.

Figure 9 is a vertical section taken substantially as indicated at line 9—9 on Figure 8.

Figure 10 is a detail section showing the pump valves and taken as indicated at line 10—10 on Figure 3.

Figure 11 is an end elevation of the bowl or receptacle casting.

Figure 12 is a detail section on an enlarged scale to show the construction of the automatic air leak or vent.

As shown, the apparatus is housed in a metallic casing which may be a casting of any suitable metal, as for example, a die casting, and is shown in the form of a rectangular bowl 1 with a cover 2, the cover being formed with a flange 3 dimensioned for mating, edge to edge, with the side wall of the bowl, and the bowl having a pair of diagonally opposite corner lugs 4, 4 with threaded holes 5, 5 registering with the bolt holes 6, 6 in depressed corner sections in the web of

the cover to receive bolts 7, 7 by which the cover is secured in place, making a substantially dust-tight joint between the side walls of the bowl and the cover flange. The bowl casting includes a partition 8 cast integrally with the bottom wall 9 and side walls 10 and 11, and the cover is similarly provided with an integrally cast rib 12 positioned for mating, edge to edge, with the partition 8 so that with the cover in place the enclosed space is divided into two compartments. One compartment is designed to house the diaphragm pump and an electric motor for driving it, and is therefore ventilated through slots 13 formed in the bottom wall 9.

The pump is indicated in outline at 14 in Figures 2 and 3 as surmounting a housing 15, enclosing suitable transmission gearing and a driving pitman 16 seen in dotted outline in Figure 3 for operating the diaphragm of the pump. The driving motor includes a laminated field 17 and field winding 18 seen in Figure 3, and is supported on the casing which encloses the pump transmission. Said motor includes a fan 19 on its shaft for circulating air in the compartment and preventing overheating of the motor and associated parts.

The apparatus, being designed particularly for association with a stove heated by an oil burner, is arranged to be mounted in convenient relation to the stove, and for this purpose the bottom wall 9 of the bowl is formed with a hollow boss 20 adapted for securement to the end of a suitable post 21 upstanding from the floor of the space in which the stove is located. The boss may be provided with set screws 22 for securely fastening the bowl to the post. A fuel inflow connection from the fuel source is indicated by a pipe or tubing 23 leading into the bottom of the bowl by way of a coupling nipple 24 secured in a boss 25 formed on the bottom wall 9. The outflow connection is shown as a pipe 26 extending from a coupling nipple 27 in the bottom of the bowl, and a third pipe 28, connected into a coupling 29, serves as an overflow connection for returning fuel to the supply tank (not shown). This overflow is chiefly for the purpose of carrying off surplus fuel which might be poured in when the pump is being primed.

In the boss 25, the coupling nipple 24 enters an upwardly extending passage 30, from which a branch passage 31 leads laterally for communication with a bore 32 formed in a column 33 which is a thickened portion of the partition 8, but extends above it and above the edges of the side walls 10 and 11. A passage 34 leads from

the bore 32 to the inlet port 35 for the pump, said port being formed in a plug 36, which also houses the inlet valve 37. A substantially similar plug 38 contains the outlet port 39 and outlet valve 40 and these two plugs serve as securing means for fastening the pump head casting 41 against the upper end portion of the column 33, as seen in Figure 3. The inlet passage is restricted by the insertion of a threaded plug 42 in the lower end of the bore 32, said plug having a transverse passage 43 which communicates with the passage 31, and having also a central restricted passage 44 through which the oil must flow upwardly to reach the pump, and through which suction is exerted on the oil line by the pump.

It may be understood that the pump is of the diaphragm type, the diaphragm itself not being shown in detail, but indicated at 45 as clamped between the head casting 41 and a flange 46 at the upper end of the transmission casing. The diaphragm movement serves to draw liquid fuel in through the port 35 and expel it through the outlet port 39 which communicates with a discharge passage 47 leading downwardly from the pump connection through the column 33 and opening into a notch or recess 48 in the bottom of the column just above the bottom wall 9 of the bowl. In this way the fuel compartment 49 is filled with liquid up to the predetermined level at which the accumulation of fuel is to be arrested. This may be substantially at the level of overflow ports 50 formed in a covered well 51 in the bowl casing. The coupling nipple 29 connects this well with the overflow pipe 28 leading back to the supply tank.

As will be seen from Figure 8, the compartment 49 of the bowl which is defined by the partition 8 therein, is L-shaped in plan section, and includes an alcove 52 which accommodates the float 53 whose function is to control operation of the motor which drives the pump. As the liquid fuel accumulates in the compartment 49 and its alcove 52, the float 53 is buoyed up until, upon reaching a predetermined level, its connected rod 54 operating upon the crank 55 of a rock shaft 56 swings the tube 57 of a mercury switch to the angle at which it cuts off the current from the motor and thus halts the operation of the pump for the time being. When the fuel level in the space 52 recedes to a predetermined point, the switch 57 being rocked by the descent of the float 53 re-establishes the driving circuit for the motor, and the pump is again placed in operation to replenish the supply of liquid fuel in the bowl. The provision for current supply for the motor is indicated by the cable 58 with suitable connecting wires leading therefrom to the switch 57 and to the motor, as shown in Figure 2, but which need not be described in detail.

If a defect in the burner, or a leak in the pipe line 26 should cause the fuel to be withdrawn from the compartment 49-52, at an excessive rate, the result would be that either the burner would operate in an inefficient manner with incomplete combustion, or the unburned fuel would be spilled upon the floor adjacent the furnace, with a resultant fire hazard. There being no chance for the liquid to accumulate in the bowl, the float 53 would not be lifted to its upper limit, and the switch 57 would not be operated to stop the motor and pump. Under these conditions, it is desirable that the continued operation of the pump shall not continue to draw liquid fuel from the supply source and pass it into the compartment 49-52 from which it would continue to

flow through the leak in the line, or into the defective burner. Therefore, the inlet passage 30 is provided with a second lateral branch 59 connecting into a passage 60 which leads upwardly adjacent the float 53 and which is threaded at 5 61 to receive a threaded plug 62. The threads of the plug 62 are fitted loosely in the threads 61 of the passage so as to provide an air leak around said threads, as clearly shown in Figure 12. When the liquid level in the space 52 recedes 10 below the upper end of the passage 60 the suction of the pump acting through the bore 32 and lateral passages 31 and 59 will be satisfied by air drawn in past the threads 61 and will fail to lift the liquid fuel through the supply line 23. 15 The remaining liquid in the space 49-52 will be depleted rapidly through the delivery pipe 26 and thereafter no more oil will be delivered from the apparatus. The burner will consequently cease to operate, and the condition will presently come 20 to the attention of the occupants of the building or the janitor in charge of the heating plant, without resulting in any serious fire hazard.

The air leak around the threads of the plug 62 also becomes effective in the event that the float 25 53 becomes perforated, or for some other reason loses its buoyancy and falls below the normal lower limit of its range to the position shown in full lines in Figure 9. In the case of a defective float, this may occur before the level of the liquid 30 has receded below the upper end of the passage 60; therefore, the plug 62 supports an upstanding guide rod 63 on which there is carried a loosely fitting sleeve 64 whose upper flange 65 normally rests on a forked arm 66 extending more 35 from the float 53 and holding the lower flange 67 of the sleeve 64 above the upper end of the passage 60. But when failure of the float allows it to descend below the normal low limit of its range, the sleeve 64 is lowered onto 40 the upper surface of the boss in which the passage 60 is formed, and the sleeve 64 thus becomes an extension of the passage reaching above the level of liquid in the chamber 52 and conducting air to the upper end of the passage 60 and thence 45 through the air leak around the threads of the plug 62. Thus enough air is supplied through the branch 59 to the intake 34 of the pump to satisfy suction of the pump and prevent more liquid from being drawn in through the inlet pipe 23. 50 Presently, the supply of liquid in the space 49-52 will be depleted by the burner, and the latter will cease to operate, calling attention to the fact that the device is out of order and requires 55 attention.

The air leak afforded by the looseness of the threads of the plug 62 in the threaded bore 61 may be made adjustable in various ways. As shown in Figure 12, the threads 61 are formed in a bushing 68 fitting tightly in the upper end 60 of the passage 60 but of substantially the same length as the plug 62. Thus, when the plug is screwed downwardly so that a portion of it protrudes from the lower end of the bushing into the larger bore 68, the effective length of the 65 helical air vent between the threads which are still in engagement is reduced, and the friction of the vent passage is thus reduced so as to vary its effect as a vent. A spring 69 pocketed in the lower portion of the passage 60 bears against 70 the lower end of the plug 62 for holding it in adjusted position.

To ensure the elimination of dirt from the liquid fuel the plug 42 is formed with a reduced portion registering with its transverse passage 75

43 and an annular screen 70 is secured in the recess thus formed in the surface of the plug. Occasionally, it may be necessary to prime the apparatus in starting it, and for this purpose 5 the cover is formed with a filler opening fitted with a screen 71 through which liquid can be poured in; the opening is provided with a swinging cover 72 and registers with the L-shaped compartment 49—52 in which the liquid is 10 cumulated, and from which it flows to the burner or other point of use.

From Figure 3 it will be noted that the heads of the plugs 36 and 38 engage one side of the column 33 while their threaded ends draw the 15 pump body 41 against the other side of the column, and that this provides the sole support of the pump in the receptacle or housing 1 but entirely out of contact with its walls. This arrangement tends to ensure quietness of operation 20 because any tendency to vibration is absorbed in the motor and pump structure before it leaves the housing 1; hence, the housing does not contribute any resonance or amplifying effect in the event of such vibration.

25 While there is shown and described herein certain specific structure embodying the invention, it will be manifest to those skilled in the art that various modifications and re-arrangements of the parts may be made without departing from the spirit and the scope of the invention, and that the same is not limited to the particular form herein shown and described, except in so 30 far as indicated by the appended claims.

I claim:

- 35 1. In a liquid feeding device, a pump, an electric motor connected to drive the pump, a chamber into which the pump delivers the liquid, a float in the chamber responsive to changes of liquid level therein, and an electric switch for 40 the motor connected for actuation by said float, a suction line leading to the pump and a vent passage from said line having an opening in the chamber but normally submerged by the liquid therein, an extension tube for said vent, normally 45 disconnected therefrom and means actuated by the descent of the float below its normal lower limit serving to connect the extension to the vent for shifting the effective vent opening to a higher level.
- 50 2. In a liquid feeding device, a pump, an electric motor connected to drive the pump, a chamber into which the pump delivers the liquid, a float in the chamber responsive to changes of liquid level therein, and an electric switch for 55 the motor connected for actuation by said float, a suction line leading to the pump and a vent passage from said line having an opening in the chamber but normally submerged by the liquid therein, said vent passage opening upwardly, an extension tube carried by the float above the vent opening throughout the normal range of float movement but adapted to be lowered into connection with said opening when the float falls below its normal low limit, whereby the effective vent opening is shifted to a higher level.
- 60 65 3. In a liquid feeding device, a pump, an elec-

tric motor connected to drive the pump, a chamber into which the pump delivers the liquid, a float in the chamber responsive to changes of liquid level therein, and an electric switch for the motor connected for actuation by said float, 5 a suction line leading to the pump and a vent passage from said line having an opening in the chamber but normally submerged by the liquid therein, said vent passage including a threaded bore and a threaded plug loosely fitted and axially adjustable therein, a guide rod extending upwardly from the plug, a tube loosely slideable on said rod and an arm on the float engaging the tube normally supporting it above the opening of the vent but adapted to lower the tube into connection with said opening when the float falls below its normal low limit, whereby the effective vent opening is shifted to a higher level.

4. In a liquid feeding device, a receptacle provided with a vertical partition dividing it into two compartments, an electric motor and a pump driven thereby in one compartment, the other compartment serving as a receiving chamber for the liquid, the partition having a pair of vertical passages, an inlet connection leading from a liquid supply source into the lower end of one passage, the other passage having a discharge opening in the lower part of the receiving chamber, the partition having a pair of transverse passages into which the upper ends of the vertical passages respectively open, the transverse passages connecting with intake and discharge ports respectively of the pump, said transverse passages extending through the partition, and hollow plugs each having a head at one end and having its opposite end threaded for supporting the pump body on the partition, said plugs having passages which connect the passages of the partition with the ports of the pump.

5. In a liquid feeding device, a receptacle provided with a vertical partition dividing it into two compartments, an electric motor and a pump driven thereby in one compartment, the other compartment serving as a receiving chamber for the liquid, said partition having a pair of vertical passages, an inlet connection leading from a liquid supply source into the lower end of one passage, the other passage having a discharge opening in the lower part of the receiving chamber, the partition having also a pair of transverse openings near the top, the pump including a body portion containing inlet and exhaust ports and fitted against said partition at one side, a pair of hollow plugs extending through said transverse openings having heads engaging the opposite side of the partition with internal passages respectively connecting the vertical passages of the partition with the ports of the pump and having threaded end portions engaging in the pump body for supporting it, said connection providing the sole support for the pump in the receptacle, and means by which the motor is mounted upon the pump body and wholly supported thereby out of contact with the walls of the receptacle.

THOMAS F. SPACKMAN.
